UNITED STATES PATENT OFFICE.

GEORGE B. STARR, OF OAKLAND, CALIFORNIA, ASSIGNOR OF ONE-HALF TO O. J. MEADS,
OF OAKLAND, CALIFORNIA.

AUTOMATIC ALARM TIME-CLOCK.

1,108,636.

Specification of Letters Patent.

Patented Aug. 25, 1914.

Application filed January 21, 1913. Serial No. 743,299.

To all whom it may concern:

Be it known that I, GEORGE B. STARR, a citizen of the United States, residing at Oakland, in the county of Alameda and

State of California, have invented new and useful Improvements in Automatic Alarm Time-Clocks, of which the following is a specification.

This invention relates to an automatic timer which can be set to run a definite period of time, and to notify the operator at the expiration of that time.

The invention has been particularly applied in practice in keeping track of time in cooking eggs, etc., having been successfully used as an automatic alarm egg timer. Manifestly, however, it is capable of general use wherever lapsed time is to be kept track of.

20 The invention consists of the parts and the combination and construction of parts as hereinafter more fully described and claimed, having reference to the accompanying drawings, in which—

25 Figure 1 is a front elevation of the apparatus. Fig. 2 is a front elevation of the operating mechanism. Fig. 3 is a plan view of Fig. 2. Fig. 4 is a detail vertical section on line X—X, Fig. 3. Fig. 5 is a detail vertical section on line Y—Y, Fig. 3. Fig. 6 is a detail perspective view of the locking and releasing mechanism.

A is a dial which may be graduated by minutes and fractions thereof, or other desired sub-divisions of time.

2.5 2 is an indicator or hand traveling over the dial. This indicator is mounted on a shaft 3 which is acted on by the main spring 4 and adapted to be turned against the tension of said spring by suitable means, as the key 5. Shaft 3 carries a mutilated gear 6 constructed and arranged, when the shaft 3 has been turned against the tension of its spring a pre-determined distance, to engage a gear 7 arranged in the alarm system after the following manner: Gear 7 is mounted loose on what I shall term the alarm shaft 8, which latter may be wound against the tension of its spring 9. 10 is a ratchet wheel fixed on shaft 8 and operated on by a spring-pressed pawl 11 on the loose gear 7. Turning the key 5 to the left to wind up spring 4 also turns the mutilated gear 6, which latter when it engages with the loose gear 7 will lock gear 7 to shaft 8

by its pawl 11 and ratchet 10, to turn the alarm shaft 8 against the tension of its spring 9 to wind the alarm mechanism.

The alarm mechanism which I have shown comprises in addition to the foregoing parts, the following train of gears:— 12 is a loose gear on alarm shaft 8 carrying the pawl 13 adapted to engage a ratchet 14 fixed on alarm shaft 8. Loose gear 12 engages a pinion 15 on a counter-shaft 16, 45 which latter carries a spur gear 17 which operates the alarm lever in the manner well known in the art. Lever 18 carries a hammer 19 to sound the bell 20.

In addition to the indicator hand 2, the main shaft 3 carries a trip finger 21 adapted to engage a bell crank 22, which operates a spring detent 23 normally disposed in the path of the alarm lever 18. The alarm can not go off until the trip finger 21 engages 75 the bell crank and moves the spring detent 23 to release the arm.

The operation of the device is as follows: If for instance the device is used as a timer for indicating the length of time an egg is 50 to be boiled, the key 5 with the indicator hand 2 standing at zero is turned to the left to the point marked "3 minutes" on the dial, or such other time for which the egg is to be boiled, at the same time the article is 55 deposited in the hot water. This turning of the key winds up the mechanism. Immediately on the release of the key the mechanism acting under the tension of the main spring 4, governed by the usual escapement 60 and balance common in clocks and not necessary here to be shown or described, the hand 2 gradually moves backward over the dial until the indicator or hand 2 returns to zero. Simultaneously, with the return of 65 the indicator to zero the trip finger 21 on shaft 3 engages the bell crank 22 and operates the spring detent 23 to release the pressure on the alarm lever 18. Since the alarm mechanism is now free to turn, the mutilated portion of the gear 6 allowing the gear 7 to 70 turn free. By this construction the indicator 2 normally stands at the zero mark on the dial, which point is the initial point from which time is computed. When the clock is set it is set with reference to the ini- 110

tial position of the indicator and when the indicator returns to initial position the alarm is released and not before. The key 5 operates to turn the indicator in one direction and the spring 4 to return it to initial position; there being no dogs or catches on the main shaft the latter begins its return movement immediately on the release of the key and the spring is wound only sufficient to run the timer for the particular period of time of three minutes, or three hours, or whatever other time the timer is set for.

Having thus described my invention, what I claim and desire to secure by Letters Patent is:

1. In an automatic alarm timer, a spring actuated winding shaft, alarm mechanism, means to hold the alarm inoperative, means whereby operation of the winding shaft winds said alarm mechanism, including a member which is disengaged from the alarm mechanism after the winding shaft has moved a predetermined distance, and means operated by the winding shaft to release the alarm mechanism holding means after disengagement of said member from the alarm mechanism.

2. In an automatic alarm timer, a winding shaft, alarm mechanism, means to hold the alarm inoperative, means operative by said

shaft for winding the alarm mechanism and being moved out of operative engagement with the alarm mechanism when the shaft has traveled a predetermined distance, and means operated by the shaft to release said means which holds the alarm inoperative after the winding means has been disengaged from the alarm mechanism. 35

3. In an automatic alarm timer, a spring actuated winding shaft, a mutilated gear on said shaft, alarm mechanism including a spring actuated alarm shaft and a hammer carrying lever, means for winding the alarm shaft from the gear, a trip finger carried by said winding shaft, a bell crank arranged to have one arm thereof engaged by said trip finger, a spring detent normally disposed in the path of the hammer carrying lever, and means carried by the other arm of the bell crank to actuate said detent to release the hammer carrying lever after the gear has been disengaged from the winding means. 40

In testimony whereof I have hereunto set my hand in the presence of two subscribing witnesses.

GEORGE B. STARR.
